(57) **CLAIM**

The ornamental design for an arrowhead with curved blades, as shown and described.

DESCRIPTION

FIG. 1 is a first perspective view, from a front-top-right angle, of an arrowhead with curved blades incorporating my new design, in a first embodiment;

FIG. 2 is a second perspective view thereof from a front-top-left angle;

FIG. 3 is third perspective view thereof from a rear-right-top angle;

FIG. 4 is fourth perspective view thereof from a rear-top-left angle;

FIG. 5 is a top view thereof;

FIG. 6 is a bottom view thereof;

FIG. 7 is a right plan view thereof;

FIG. 8 is a left plan view thereof;

FIG. 9 is a front view thereof;

FIG. 10 is a rear view thereof.

FIG. 11 is a first perspective view, from a front-top-right angle, of an arrowhead with curved blades incorporating my new design, in a second embodiment;

FIG. 12 is a second perspective view thereof from a front-top-left angle;

FIG. 13 is third perspective view thereof from a rear-right-top angle;

FIG. 14 is fourth perspective view thereof from a rear-top-left angle;

FIG. 15 is a top view thereof;

FIG. 16 is a bottom view thereof;

FIG. 17 is a right plan view thereof;

FIG. 18 is a left plan view thereof;

FIG. 19 is a front view thereof; and,

FIG. 20 is a rear view thereof.

In the above figures, the broken lines form no part of the claimed design.

1 Claim, 12 Drawing Sheets
